UNITED STATES PATENT OFFICE.

JOHN THOMAS WHITTOME, OF TAVISTOCK, ENGLAND.

COMBINED STREET-SWEEPER AND COLLECTOR.

1,001,107.

Specification of Letters Patent. Patented Aug. 22, 1911.

Application filed May 10, 1907. Serial No. 372,950.

To all whom it may concern:

Be it known that I, JOHN THOMAS WHITTOME, residing at Parkwood Road, Tavistock, in the county of Devon, England, 5 have invented a Combined Street-Sweeper and Collector; and I hereby declare that the following is a full, clear, and exact description of the same.

This invention relates to a combined 10 street sweeper and dirt collector, which will sweep the dirt from the surface over which the apparatus passes, collect it into a receptacle provided for that purpose, and convey it by an elevator or carrier from the receptacle to a cart or wagon.

It further relates to a means for automatically moving the dirt in the receptacle into the path of the elevator or carrier, and to a means by which the elevator or carrier is 20 enabled to pass any obstacle which enters its path.

For an understanding of the invention reference is to be had to the following description and to the accompanying drawings, in which,

Figure 1, is a side elevation of a sweeper and cart with one side of the elevator removed. Fig. 2, is a side elevation of a sweeper, showing a modification of the construction illustrated in Fig. 1, with the elevator side removed. Fig. 3, is a rear elevation of the sweeper shown in Fig. 2, with the sweeper brush removed. Fig. 4, is a detail view of the mechanism for actuating 30 the side scrapers operating in the dirt receptacle. Fig. 5, is a plan view of the mechanism shown in Fig. 4. Fig. 6, is a detail view of one of the elevator buckets shown in Fig. 1. Fig. 7, is a detail view of one of 35 the elevator buckets shown in Figs. 2 and 3. Fig. 8, is a view showing one set of elevator scrapers. Fig. 9, is a side view of one of the scrapers shown in Fig. 8.

Like characters of reference refer to like 45 parts throughout the specification and drawings.

Referring to Fig. 1; the rotary brush B is revolvably mounted in the arms b' rockably mounted on the shaft G, journaled in 50 the sweeper frame, so that the brush can accommodate itself to the surface over which it is moving. Power is transmitted

to the brush by chains G⁴ passing over sprocket wheels G³ on the shaft G and sprocket wheels G⁵ on the brush shaft. The 55 shaft G is driven by chains G² passing over sprocket wheels G' mounted on a sprocket wheel shaft g' and other sprocket wheels (not shown) on the shaft G. The sprocket wheels G' are driven by pinions G⁶ on the 60 axle a² and pinions (not shown) on the sprocket wheel shaft g'.

The lower part of the elevator casing P forms a dirt receptacle P⁵ having an opening P', through which the dirt from the 65 brush B is thrown into the dirt receptacle. Pivoted to the lower edge of the opening P' is an apron b⁹, which together with the brush B may be vertically adjusted. This adjustment is effected by chains or cords b⁷, 70 connecting the apron b⁹ with the arms b' and the latter with the rocker beams b⁵. The rocker beams b⁵ are fulcrumed to the sweeper frame at b⁶, and pivotally connected to the rocker beams b⁵ and to the adjustment levers b⁸ are links b¹⁰. The adjustment levers b⁸ are fulcrumed to the standard b¹¹, and are operated to respectively raise or lower the brush B. Pivoted at C⁶ to the dirt receptacle P⁵ are arms C² in 80 which is mounted a shaft c' fitted with sprocket wheels c⁹, and journaled at the top of the elevator is a shaft n, on which are mounted sprocket wheels H. Passing around the sprocket wheels H and c⁹ are 85 sprocket chains C⁵ to which are secured the buckets C. Mounted on the shaft n is a sprocket wheel m driven from the shaft G, by a chain G⁷. Idlers h' are provided for the sprocket chains C⁵ immediately below 90 the sprocket wheels H. The buckets C carry the contents of the dirt receptacle over the sprocket wheels H, and deposit the said contents through the delivery spout P⁴, into the cart. The arms C² are provided with 95 studs C⁷, vertically movable in the slots C⁴ of the hanger arms C³, the latter being pivoted at C⁸ to the elevator sides, so that when an obstacle obstructs the path of the buckets C, the sprocket shaft c' can move upwardly 100 to enable the bucket or buckets to clear the obstacle, and resume its normal position by gravity when the obstacle has been passed.

Connected to the front of the sweeper is

an axle upon which may be mounted one or more guide wheels E, and attached to the front of the sweeper is a draw bar F.

The construction shown in Fig. 2, is in

- 5 many respects similar to that shown in Fig. 1, but in this case the drive wheels A', are situated closer to the elevator, and the drive wheel axle a^2 is provided with cog wheels A ^{2} meshing with cog wheels a^3 on the shaft G.
- 10 In Fig. 1, the sprocket wheels H are shown to be of greater diameter than the sprocket wheels h^4 shown in Fig. 2, and in the latter figure the idlers h' shown in the former figure are dispensed with. In Fig. 2, the adjusting levers b^8 are pivoted to the elevator frame instead of to the standards b^{11} as shown in Fig. 1, but otherwise the general principle of the construction and operation of the parts shown in Fig. 2, is the same as
- 15 that in Fig. 1.

Means are provided for moving the dirt in the dirt receptacle P ^{5} into the path of the elevator buckets C, and for scraping the dirt away from the delivery spout P ^{4} of the elevator to prevent it accumulating at that place. The means for moving the dirt in the dirt receptacle into the path of the elevator is shown in Figs. 3, 4 and 5, and may be described as comprising scrapers D working from the ends of the dirt receptacle P ^{5} toward the elevator buckets C. The scrapers D are connected to scraper arms d^9 having guide plates d^5 formed with guide slots d^{10} , to receive the crank pins d^6 , attached to the bevel wheels d^3 . The bevel wheels d^3 are mounted to revolve on studs d' projecting from the standards d^4 secured to the sweeper frame and their rotation is effected by bevel wheels d^2 on the shaft G. During the rotation of the bevel wheels d^3 the crank pins d^6 engage in the guide slots d^{10} , and move the scrapers from the position shown in the full lines, to that shown in dotted lines in Fig. 3. During the movement of the scrapers, from the position shown in full lines to that shown in dotted lines, the crank pins d^6 engage with the bottom ends of the guide slots d^{10} , and drag the scrapers along the bottom of the dirt receptacle. During the return of the scrapers from the position shown in dotted lines, to that shown in full lines, the crank pins d^6 engage at the top of the slots and lift the scrapers from the bottom of the dirt receptacle.

- 55 To prevent the accumulation of the dirt in the delivery spout P ^{4} , a scraping device is provided consisting of scrapers k provided with scraper arms k' mounted on a crank shaft k^2 driven by a chain k^3 , from the shaft n. The ends of the scraper arms k' are connected by links k^6 pivoted to the elevator frame. The rotation of the crank shaft k^2 carries the scrapers in an outward direction along the bottom of the delivery spout P ^{4} , to
- 60 65 eject the dirt resting thereon, and during the

return movement, the scrapers k are raised above the bottom of the delivery spout until they attain its inner end, when they are lowered into engagement with it.

In the operation of the apparatus the 70 drive wheels A' revolve the shaft a^2 , and the revolution of the shaft a^2 revolves the cog wheel A ^{2} , which meshing with the cog wheel a^3 causes the revolution of the shaft G. The revolution of the shaft G, through the 75 agency of the bevel wheels d^2 revolves the bevel wheels d^3 , and crank pins d^6 , to oscillate the scrapers D between the ends of the dirt receptacle and buckets C. To hold the scraper arms and scrapers in a position 80 where they will be obliged to complete the full distance of their travel, links d^{12} are connected to the scraper arms d^9 , and to a pivot plate d^{13} secured to the elevator.

I claim—

1. In a combined street sweeper and collector in combination, an axle, two ground wheels mounted thereon, a dirt receptacle suspended from the axle of the ground wheels, an elevator to remove the contents 90 of the dirt receptacle, an elevator driving means actuated by the ground wheels, two scrapers within the dirt receptacle and located one on each side of the elevator, and provided with scraper arms extending beyond the dirt receptacle, links pivoted to the scraper arms and to the elevator, and means for imparting reciprocating motion to the scraper arms and scrapers actuated by the elevator driving means. 95

2. In a combined street sweeper and collector in combination, an axle, two ground wheels mounted thereon, a dirt receptacle suspended from the axle of the ground wheels, an elevator to remove the contents of the dirt receptacle, an elevator driving means actuated by the ground wheels, two scrapers within the dirt receptacle and located one on each side of the elevator, and provided with scraper arms extending beyond the dirt receptacle, links pivoted to the scraper arms and to the elevator, slotted guide plates secured to the scraper arms, and a crank operating in the slotted guide plate rotated by the elevator driving means. 105 110 115

3. A combined street sweeper and collector comprising an elevator, consisting of an elevator casing, a sprocket shaft journaled at the upper end of the elevator casing, 120 sprocket wheels mounted thereon, arms pivotally connected to the elevator casing at the lower end thereof, a sprocket shaft journaled in said arms, sprocket wheels mounted on the last mentioned sprocket shaft, elevator chains passing around the sprocket wheels, elevator buckets connected to the sprocket chains, and guide arms to control the movement of the first mentioned arms. 125

4. A combined street sweeper and collector comprising an elevator casing, having a dirt 130

receptacle at one end thereof, a drive shaft, bevel wheels mounted on the drive shaft, bevel wheels driven by the first mentioned bevel wheels, scraper arms, slotted guide 5 plates for the scraper arms, cranks for the second mentioned bevel wheels engaging in the slotted plates, scrapers connected to the scraper arms within the dirt receptacle and

links pivotally connected to the scraper arms and to the elevator casing.

In witness whereof I have hereunto set my hand in the presence of two witnesses.

JOHN THOMAS WHITTOME.
